Inventor.
James Sangster

United States Patent Office.

JAMES SANGSTER, OF BUFFALO, NEW YORK, ASSIGNOR TO HIMSELF AND
DANIEL H. BURTIS, OF SAME PLACE.

Letters Patent No. 75,469, dated March 10, 1868.

IMPROVED MACHINE FOR CARBURETTING AIR.

The Schedule referred to in these Letters Patent and making part of the same.

TO ALL WHOM IT MAY CONCERN:

Be it known that I, JAMES SANGSTER, of Buffalo, in the county of Erie, in the State of New York, have invented certain new and useful Improvements in and on Machines for Carburetting Air; and I do hereby declare that the following description of the construction and operation of the same is sufficiently full, clear, and exact to enable others skilled in the art to which it appertains, or to which it is most nearly connected, to make, construct, and use the same, reference being had to the accompanying drawings, making a part of this specification, in which—

Figure 1 is a vertical longitudinal section of my said invention.

Figure 2, a side elevation of the air-wheel of the same.

Figure 3, a perspective view of the said wheel.

Figure 4 represents a perspective view of the air-tube chamber which forms a part of said air-wheel.

The nature of my invention consists in—

First. The combination of an air-wheel with a stationary air-tube and a non-forcing air-chamber, provided with openings which rise above the surface of the water after the air-forcing parts or chambers of the said wheel are closed by the open parts of said air-forcing chambers passing into the water, the said openings in the non-forcing air-chamber being so arranged as to allow the air which is being forced by the air-forcing chambers to pass into the said non-forcing air-chamber and air-tube, and from the said air-tube into and through the carburetting-liquid; the arrangement being such that the air or gas is forced, as the wheel revolves, directly through the carburetting-liquid, instead of having first to pass through water, as in other air-forcing wheels.

Second. In the combination of an inverted open-mouthed air-floating chamber or vessel with an air-discharging tube, the discharging end of which projects upward, above the surface of the carburetting-liquid, and within the said air-floating chamber, the weight of said air-floating chamber being so adjusted that the air will be forced into and through the surface of the carburetting-liquid downward the same distance, or nearly so, although the level of the surface of the said liquid may be changing; the pressure of the air within the said air-forcing chamber, while in action, sustaining or holding its lower edge or mouth at any distance or point to which it may be adjusted, by its weight, below the surface of the carburetting-liquid, the arrangement being such that while the machine is in action the said air-floating chamber or vessel moves up or down, as the surface of the carburetting-liquid may be moved or changed, but, at the same time, its lower edge or mouth maintains its proper position with respect to the surface of the same. Of course it will be readily seen that by this arrangement or device the air-floating chamber or vessel will immediately fall or sink into the carburetting-liquid as soon as the pressure of the air is taken from it, and rise again, as soon as the pressure is renewed or air forced into it, to its proper position.

Third. In combining with the said air-floating chamber and air-discharging tube, a supplemental tube, which surrounds the air-floating chamber and projects from above the surface of the carburetting-liquid downward through said liquid to within a short distance, say one-fourth or one half of an inch, of the bottom of the vessel holding the carburetting-liquid. By this arrangement all the liquid contained must pass under the lower end of said supplemental tube, so that all the carburetting-liquid, as it is taken up by the air passing through it, comes from the lower part of the vessel holding the same. By this means the carburetting-liquid is kept in a more equalized condition, as the heavy portions of the same, which settle at the bottom, are taken up and mingled with the upper portions of the said liquid.

Fourth. My invention further consists in making the gasometer, into which the gas is forced, of a tapering form, so that it may cause an equal pressure to be given to the gas at all times. As the ordinary gasometer descends into the water, it of course displaces a certain amount of the same, which, in the proportion of said displacement, tends to lift up or float it, thus causing less pressure on the gas as it descends into the water. By my arrangement this defect is obviated, as the gasometer presents less surface to the gas in proportion as it descends into the liquid. Its proportions should be, say, about or nearly one-fifteenth larger at the bottom than at the top.

In the said drawings, in which like letters represent like parts in the several figures, A, in the section view, represents the tapering gasometer. Its mouth or open end is sealed by water, as shown at B, into which it is moved up by the pressure of the gas. C is the outlet-tube for the gas. D represents the air-floating chamber or vessel. It is kept up in its proper position with respect to the level of the carburetting-liquid, as shown by the dotted lines G, by the pressure of the air within it, as hereinbefore mentioned. E is the discharging end of the air-discharging tube, the discharging end of which is always above the level, G, of the carburetting-liquid, as shown. F² represents the supplemental tube which surrounds the air-floating chamber D, for purposes hereinbefore mentioned. J is the carburetting-liquid vessel; it is filled through the opening O. P represents the air-forcing wheel; H, the air-forcing chambers or buckets, of which there are four, two on each side. I is the non-air-forcing chamber. The letters K represent the openings in the same, as hereinbefore mentioned. There are four of said openings, two on each side, placed at right angles to each other, as shown in fig. 2, the black dotted lines showing the openings on one side, and the red lines showing the openings on the opposite side, as and for the purposes hereinbefore mentioned. F represents the receiving end of the air-discharging tube. It projects up, as shown in figs. 1, 2, and 3, above the surface or level, T, of the water, so that there is no water or carburetting-liquid in any part of said tube, thereby leaving a clear passage for the air through it, but no opening whatever for either water or carburetting-liquid, as one end is always above the water and the other above the carburetting-liquid. In fig. 3, U represents the open side of one of the air-forcing buckets or vessels H, and K, within it, the position of the opening in the non-forcing air-chamber, showing its position with reference to the open parts of said openings U in the air-forcing chambers. W, in the same figure, shows the closed back end of one of the said chambers H. The air-tube is fastened stationary at the points S S, and the air-wheel is made to revolve around said tube in the direction of the arrows shown near the letter I, in fig. 3. Motion is given to the air-wheel by the usual machinery gearing into the pinion X, and a weight.

What I claim as my invention, and desire to secure by Letters Patent, is—

1. The combination of an air-forcing wheel with a stationary air-tube and a non-forcing air-chamber, I, provided with openings K, the whole being constructed to operate substantially as and for the purposes herein set forth and described.
2. The combination of an air-floating vessel, D, and an air-discharging tube, the discharging end E of which projects above the carburetting-liquid, as and for the purposes substantially described.
3. The supplemental tube F², as and for the purposes substantially as described.
4. The tapering movable gas-holder A, as and for the purposes substantially described.

JAMES SANGSTER.
